Des. 219,679
Patented Jan. 5, 1971

219,679

LINKAGE FOR AN IDENTIFICATION BRACELET OR SIMILAR ARTICLE

Raymond C. Fontaine, Greenville, R.I., assignor to Textron Inc., Providence, R.I., a corporation of Delaware

Filed Oct. 13, 1969, Ser. No. 19,537

Term of patent 14 years

Int. Cl. D11—01

U.S. Cl. D45—4

FIG. 1

FIG. 2

FIG. 3

FIG. 4

FIG. 1 is a top plan view of a linkage for an identification bracelet or similar article, showing my new design; FIG. 2 is a side elevation;

FIG. 3 is an end view looking from left to right at FIG. 1; and

FIG. 4 is a perspective of the linkage shown in FIG. 1. I claim:

The ornamental design for a linkage for an identification bracelet or similar article, substantially as shown.
